UNITED STATES PATENT OFFICE.

JOSEPH GALLEAZZI, OF SAN FRANCISCO, CALIFORNIA.

ACCORDION PLATE.

Application filed October 24, 1925. Serial No. 64,584.

This invention relates to improvements in accordions and more particularly to the mechanism for operating the valves of the accordion, the main object being to provide a simplified form of valve operating mechanism which will materially reduce the weight of the accordion, lessen the cost of manufacture and simplify the operation thereof.

One of the objects of the invention is to provide an operating mechanism of the character described whereby the usual number of chords in each key, may be played with less fingering and effort than has heretofore been possible and furthermore with less mechanism than has heretofore been used, the said mechanism operating to produce a major chord in a given key, upon the depression or movement of a given operating key of the ordinary key board, and to then produce four other chords in the same key upon operation of another operating member, thus providing for the playing of five chords in any key upon the operation of but two operating elements which may be easily fingered or operated.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Referring to the drawings:

Fig. 1 represents a top plan view of the valve operating mechanism showing parts of the accordion with which the said mechanism is associated.

Fig. 2 represents a fragmentary vertical sectional view taken through a part of the accordion showing a detailed arrangement of the valve operating mechanism of the invention.

Fig. 3 represents a top plan view of a part of the valve operating mechanism.

Fig. 4 represents a diagrammatic view of the valve operating mechanism showing the inter-relation and an association of the various component parts of said mechanism.

Figs. 5 to 9 inclusive are diagrammatic views showing the relation of the control plates and associated elements of the mecha-

nism when said plates are in their five positions of adjustment.

Fig. 10 is a top plan view showing the arrangement of operating keys.

Fig. 11 is a sectional detail of lever and guide piece.

In the embodiment of the invention shown in the accompanying drawings, 1 designates the main body or box with which the reeds and bellows, not shown, are associated. A partition 2 is mounted in the box and is provided with two sets of openings 3 and 4 which are controlled by sets of valves designated 5 and 6 respectively. When these valves are opened, the reeds are vibrated in the customary manner and said reeds and valves are related as is customary in instruments of this kind. Between the partition plate 2 and the upper side of the box is a space in which is mounted the operating mechanism of the invention. This operating mechanism is primarily operated by means of a plurality of plungers or keys, generally designated 7, mounted on a key board 8 arranged on a side wall of the box 1, there being a key for each of the valves. Extending from these keys are a plurality of rods 9 which are pushed rearward or inward when the keys are depressed. The inner ends of these rods are pivoted to two sets of bell cranks 10 and 10^a, which cranks are pivoted as at 11 on a bar 12. The bell cranks 10 are fixed to the base valves 5, whereas the other bell cranks 10^a are free from connection with the valves, as will be later described.

Expansion springs 13 are mounted in recesses 14 in the bar 12 and bear against both sets of bell cranks to normally hold the valves closed. The bell cranks 10 extend past the point of their connection with the valves 5 and engage under projections 15 extending from the valves 6. Thus, when said valves 5 are raised and opened, the valves 6 will be correspondingly raised and opened. When one of the tonal keys which operate the valves 5 is depressed, and one of the valves 5 is opened, a corresponding valve 6 is likewise opened. This produces one of the notes of the scale.

The rods 9 of the other or chord keys, are connected with the other bell cranks 10^a, which latter instead of being connected with the base valves are extended between and above said base valves and at their free ends are provided with lateral extensions 16 on the outer ends of which are upward pro-

jections 17. These bell cranks 10^a are a connecting medium between the chord keys and the remaining valve operating mechanisms, which latter when operated produce chords 5 of the selected key of the scale.

The operating mechanism for producing the chords comprises twelve plate-like members mounted so that they may be moved bodily as one from a normal into four other positions upon manipulation of a single operating member located in convenient relation to the key board. These twelve members and associated mechanisms comprise a means of connection between inter-connected elements for simultaneously opening groups of the treble valves 6, and the twelve bell cranks 10^a operated by the chord keys. Each of the movable members is in the form of a rectangular plate 18 which is hinged to a rod 19 supported on slides 20 mounted on blocks 21 supported by the partition 2. The plates are therefore adjustable bodily back and forth and capable of independent swinging action on their hinges. The slides 21 are provided with extensions 22, the outer ends of which are connected with crank arms 23 extending from a shaft 24 mounted in the box 1. The shaft 24 carries a crank arm 25 which extends upwardly into an opening 26 provided in the lid or closure 27 for the box 1. This arm is adapted to be engaged by a downward projection 28 carried on a slide member 29 supported in a bracket 30 on the upper side of the lid 27. A chord changing lever 31 pivoted as at 32 on the lid 27 and at a point intermediate of its ends, is provided with an opening, in which opening is engaged a pin 34 carried by the slide 29. The chord changing lever 31 when rocked will cause the slide 29 to move and the pin 34 engaging the crank arm 25 will cause the shaft 24 to turn or rock. The projections 22 carry pins 35 which are engaged with springs 36 fastened to the box 1 in such manner that said springs are placed under tension upon movement of the plates 18, and parts connected therewith. These springs are arranged to normally hold the plates 18 and associated parts in such position that when 50 one of the chord keys is depressed, a minor or dominant chord of the selected key, will be played. These springs also serve to hold the lever 31 in a normal position such that the lever may be moved into two operative 55 positions in either direction. On moving the lever to the right, two chords will be produced and on moving it to the left, two other chords will be produced. Upon each movement of the lever the plates 18 are moved 60 into different positions as will be later more fully described, thereby producing the different chords. The lever 31 is so arranged with respect to the keys 7 that said keys and lever may be conveniently operated with one hand. The outer end of the lever may be

suitably shaped to accommodate the thumb. To designate the different operative positions of the lever there is provided adjacent the outer end of the lever, a guide piece 37 which has a central depression 38 with which the lever engages when in normal position. On either side of this depression are small shoulders 39 and 40 which check the movement of the lever at these points to designate the positions of the lever to produce different chords. Adjacent the ends of the member 37 are further shoulders 41 and 42 which indicate the positions of the lever to produce two other chords. These obstructions on the member 37 check the movement of the lever sufficient to aid the operator in holding the lever in the proper positions.

Rotatably mounted above the partition 2 are a plurality of parallel spaced shafts 43. From each shaft 43 and arm 44 extends beneath the row of plates 18 and rests on top of the lateral extensions 16 of each of the crank arms 10^a. By this arrangement when one of the bell cranks 10^a is rocked, the arm 44 resting on the extension 16 of said bell crank is raised and causes one of the rods 43 to be turned. Loops 45 are fastened to the valves 6 and extend upward around the arms 44 so that on the raising of said arms, the valves 6 are opened. To provide for the opening of other of the valves 6 simultaneously with the opening of the valve 6 which is directly opened by the loop 45, said shafts 43 each have a plurality of levers 46 fixed thereto and extended over the members 18. The levers 46 have downward projections 47 adapted to engage the members 18. Thus, when a chord key 7 is depressed and one of the bell cranks 10^a is rocked, one of the valves 6 is opened by the lifting of the arm 43 and the upward pull on the valve through the loop 45, causes other of the valves to open so that other notes in harmony with the note produced by the first named valve will be played and a chord will be produced. When the plate 18 above said bell crank is raised, it engages certain of the projections 47 of certain arms 46, and causes said arms to be lifted. This turns certain of the shafts 43 and raises the arms 44 extending from said shafts. On raising of these arms 44, the loops 45 lift the valves. By varying the positions of the plates 18, different of the arms will be raised and different valves 6 opened whereby different chords will be played.

The members or plates 18 are each provided with a plurality of cuts or recesses 49 and projections 50 so arranged that each plate 18 will operate a group of six of the arms designated 46, but not the entire group simultaneously. In one position the plates will operate two of the arms 46, in another three, and so on, there being many combinations possible with this arrangement as will

be apparent in Figs. 4 to 9 inclusive of the drawings.

In the operation of the accordion, when one of the keys 7 is depressed to produce a given note, the rod 9 is pushed inward and rocks the bell crank 10 so that two of the valves 5 and 6 are opened simultaneously. In this way the different notes of the scale may be produced as is customary in the art.

To play chords, one of the chord playing keys 7 is depressed, for example the key for producing the note C, and the bell crank 10^a is thereby rocked. At this time the plate 18 for producing the chords in the key of C, is in its normal position as shown in Fig. 7. The entire group of plates 18 being then in the position shown in Fig. 4. As the forward end of the bell crank 10^a thus operated is lifted, the projection 17 pushes upward the member or plate 18 with which it engages. The projection 47 for the rods 46 which operate the valves producing E and G notes, are the only projections of the group which are engaged by the plate 18, as said plate is swung upwardly. However, the arm 45 which is connected with the valve for producing the C note, through the instrumentality of the loop 45 is raised and the said C valve is opened. When the projections 47 on the arms 46 which control the E and G valves are pushed upwardly, said arms 46 are pushed upward and cause those of the shafts 43 to which they are connected, to rotate. As these shafts rotate, the arms 44 extending therefrom to the E and G valves are raised and through the loops 45 associated therewith, lift and open the E and G valves. In this way the C, E, and G, valves are opened and there is produced or played a tonic or major chord in the key of C. By holding the C chord key depressed, another chord in this key, for example the chord of the seventh, may be played. To do this the operator engages the chord changing lever 31 and pushes it inward against the first stop or shoulder 40. This moves the rows of plates or members 18 into the position shown in Fig. 8, and the plate 18 for the key of C will then operate on the arms 46 which are associated with the #A, E and G, valves, the other projections for the rods associated with said plates being avoided by the plate when the latter is shifted from position shown in Fig. 7 to position shown in Fig. 8. The projections 46 are of such shape that as the plate 18 is moved, certain portions of said plate will engage said projections and lift up said arms 46, the #D, E and G arms (see Fig. 8). When these arms are raised, the shafts 43 from which they are extended, are turned and the arms 44 carried by said shafts are raised and through the links 45 open the #A, E and G valves.

To play the augmented or jazz chord in

this same key, the lever 31 is pushed further inward to engage the stop or shoulder 31 and this shifts the plate 18 into position shown in Fig. 9, such that the projections 47 on the arms 46 associated with the E, #G valves will be engaged and lifted. This will cause the E and #G valves to be opened in the same manner as the valves previously described, the shafts 43 being turned and lifting on the arms 44 which are connected with the E and #G valves, by means of the loops 45.

To play the minor or diminished chords in the key of C, the operator pushes the lever from its neutral position outward against the stop 39, still holding the key of C 7, depressed and this shifts the plate 18 into the position shown in Fig. 6, whereby the arms 46 for the G and #D valves are operated as the plate is shifted, this causing the G and #D valves to be operated as previously described.

To play the diminished chord in this key, the operator pushes the valve 31 further outward against the stop 42 and the arms 46 associated with the #D, and A valves are operated in the same manner as are the other valves previously described. When the operator releases the lever 31 the spring 36 operates to return the lever and its associated parts including the rows of plates 18 to normal position. In this way it is seen that by the manipulation of a single operating element into four different positions, four different chords may be played in any given key. The operating member is arranged so that it may be moved into any one of four different positions from its neutral position, selectively. With one of the keys 7 and the chord changing lever 31, it is possible to play a plurality of chords in a given key with ease and accuracy, four of the chords being played on the shifting of the lever while the key board is held depressed. While I have shown a mechanism which will provide for five different chords in a given key, it is to be understood that it may be arranged to play a greater number of chords, if desired.

I claim:

1. The combination with an accordion which includes a plurality of valves which are opened for the purpose of playing different notes of the scale, of a plurality of movable operating members, an arm carried by each operating member, means of connection between the arms and the valves providing for opening of the valves on movement of the arms and operating members, a plurality of levers fixed to and extending from each of said operating members, on movement of which levers said operating members are likewise moved and move the arms carried thereby, a frame slideable on the accordion, a plurality of angu-

lar plates pivotally mounted upon said frame and movable on their pivots bodily into and out of engagement with said levers, a plurality of push button keys, a bell 5 crank for each key, a rod connecting each key with a bell crank, said bell cranks being arranged to engage and lift said plates when rocked, said arms being engaged with and arranged to be moved upwardly by said bell 10 cranks and means for shifting said plates bodily into different positions with respect to said levers.

2. An accordion including a plurality of valves which are opened for the purpose of 15 playing different notes of the scale, a plurality of devices for independently opening said valves, a plurality of devices for simultaneously opening groups of said valves, which last named means includes a plurality 20 of plates movable bodily into a plurality of different positions and pivoted in order that they may be swung on said pivots, which plates are constructed so that when in different positions will cause different groups 25 of valves to be simultaneously operated.

3. An accordion including a plurality of valves which are opened for the purpose of playing different notes of the scale, a plurality of rotatable rods, an arm extending 30 from each rod, means of connection between the valves and said arms providing for opening the valves when said rods are turned and the arms are moved, a plurality of levers extending from each rod and on 35 movement of which said rods are turned, a plurality of pivoted and bodily movable plates of angular formation, each of which plates is adapted to engage and move a plurality of said levers, which plates when 40 moved into different positions will engage between said levers, means for shifting the plates bodily into different positions, a plurality of members adapted to engage and push the plates upward on their pivots, 45 with which members said arms engage so as to be likewise pushed upwardly and a plurality of devices for operating said last named members.

4. An accordion including a plurality of 50 valves which are opened for the purpose of playing different notes, a plurality of rotatable rods, a plurality of arms extending from said rods, a plurality of members connecting said arms with said valves, a plurality 55 of levers extending from each rod and on movement of which levers the rods are rotated, a plurality of pivotally mounted plates shiftable into different positions, which plates when in one position are adapted 60 to engage certain of the levers and when in other positions are adapted to engage and rock other of the levers, means for simultaneously shifting the plurality of plates and means for individually rocking the plates 65 on their pivots, which last named means

includes members adapted to move into engagement with and lift both said arms and said plates

5. An accordion including a plurality of valves which are opened for the purpose of 70 playing different notes, a plurality of rotatable rods, a plurality of arms extending from said rods, a plurality of members connecting said arms with said valves, a plurality of levers extending from each rod 75 and on movement of which levers the rods are rotated, a plurality of pivotally mounted plates shiftable into different positions, which plates when in one position are adapted to engage certain of the levers and when in other positions are adapted to engage and rock other of the levers, means for simultaneously shifting the plurality of plates, means for individually rocking the plates on their pivots, which last named means includes members adapted to move into engagement with and lift both said arms and said plates and spring means for returning said plates to normal position.

6. An accordion including a plurality of valves which are opened to play certain notes of the scale, a plurality of rotatable rods, a plurality of arms extending from and which are moved on rotation of the rods, loops extending upwardly from the valves and through which loops said arms extend, a plurality of levers each of which is connected with each of said rods, which levers when rocked cause the rods to rotate, a plurality of plates each of which is adapted to engage a plurality of said levers, means upon which said plates are pivotally mounted, which means is slidably mounted on the accordion, said plates being arranged to engage certain groups of levers when in one position and other groups of levers when in other positions, means for collectively shifting said plates into different positions and means for selectively rocking said plates on their pivots, which last named means comprises push button keys, rods extending from and which are actuated by said keys, bell cranks connected with and which are rocked by said rods, projections on the bell cranks adapted to engage and rock said plates, through which projections said arms extend and spring means normally holding said plates in one of its positions.

7. In an accordion a plurality of valves, means for simultaneously opening groups of said valves including levers and a plurality of angularly constructed plates each of which plates is adapted to engage a plurality of said levers, means for simultaneously and bodily moving said plates into different positions, said plates being constructed to cause relative groups of levers to be engaged when in one position and other groups of levers to be engaged when in another position, means for pivotally mounting said

plates on the accordion and means for selectively and independently rocking the plates on their pivots.

8. An accordion including a plurality of 5 valves, a plurality of rods rotatably mounted on the accordion, a plurality of arms fastened to said rods, a plurality of upstanding loops on the valves through which said arms extend, a plurality of levers fastened to and 10 extending from each rod, a plurality of projections on the free ends of the levers, a plurality of angularly constructed plates each of which is adapted to engage a plurality of levers, a plurality of projections, a carriage 15 slidable on the accordion and on which said plates are pivotally mounted, means for sliding the carriage and moving the plates into different positions and means for selectively and independently moving the plates on 20 their pivots into engagement with said projections, which means comprises depressible keys, a plurality of rods connected with the keys, a plurality of bell cranks pivoted on the accordion and which said last named 25 rods are connected, projections on the bell cranks adapted to engage and rock the plates on rocking of the bell cranks, which projections engage and are adapted to move said arms, and spring means normally holding 30 the carriage in one of its positions.

9. In an accordion a plurality of valves, means for simultaneously opening the valves of a selected group of valves to produce a chord, which means includes a single operating element which, when depressed, will cause the valves of said selected group to be simultaneously opened and means on movement of which, while the first named means is in operation, will cause a different group of valves to be opened to play different chords, 35 which last named means includes a single operating lever movable into different positions and which when in each of its separate positions will cause a different chord to be played. 40

10. An accordion comprising a plurality of valves, means for simultaneously opening any one of certain groups of valves, which when opened, will produce a given chord in a given key and means which after operation 50 of the first named means, provides for selectively opening other valves within a given group related to a given key in order to produce different chords in said key, which last named means includes a single operating lever movable into a plurality of different positions to cause the different chords of a given key to be played. 55

JOSEPH GALLEAZZI.
